UNITED STATES PATENT OFFICE

162,327

FABRIC OR THE LIKE FOR GRILLES OF RADIOSJohn A. MacIntyre, Barrington, R. I., assignor to
B & M Mills, Inc., a corporation of Rhode Island

Application November 18, 1950, Serial No. 13,041

Term of patent 14 years

(Cl. D92—1)

To all whom it may concern:

Be it known that I, John A. MacIntyre, a citizen of the United States of America, residing at Barrington, county of Bristol, State of Rhode Island, have invented a new, original, and ornamental Design for a Fabric or the like for Grilles of Radios, of which the following is a specification, reference being had to the accompanying drawing forming a part thereof:

The figure is a plan view of a fabric or the like for grilles of radios showing my new design.

I claim:

The ornamental design for a fabric or the like for grilles of radios, substantially as shown.

JOHN A. MACINTYRE.
